UNITED STATES PATENT OFFICE

JOSEPH PSAILA, OF BROOKLYN, NEW YORK

MILK-BOTTLE HOLDER

Application filed August 19, 1929. Serial No. 386,949.

This invention relates to improvements in milk bottle holders.

The primary object of the invention resides in a box like device to which access may be had only by the authorized persons having the proper key to remove the bottle of milk therefrom after the same has been deposited therein by the milkman, thus preventing theft of the milk by unscrupulous persons. The holder also prevents the bottle of milk from becoming contaminated with germs likely to be transmitted thereto by cats and dogs, which domestic animals habitually lick the tops of milk bottles.

Another object of the invention is to provide a milk bottle holder in which a pair of spring actuated doors coact to close a bottle entrance opening, and a member carried by one of the doors for automatically seating upon the top of the milk bottle placed in the holder to lock the doors against opening.

With these and other objects in view, the invention resides in the certain novel construction, combination and arrangement of parts, the essential features of which are hereinafter fully described, are particularly pointed out in the appended claims, and are illustrated in the accompanying drawing in which;

Figure 1 is a perspective view of my improved milk bottle holder.

Figure 2 is a vertical sectional view therethrough illustrating the position of the doors upon the insertion of a bottle of milk into the holder.

Figure 3 is a similar view but showing the milk bottle in position within the holder.

Figure 4 is a vertical transverse sectional view on the line 4-4 of Figure 3.

Figure 5 is a horizontal sectional view on the line 5-5 of Figure 3 looking in the direction of the arrow.

Referring more particularly to the drawings, the reference character 10 designates my improved milk bottle holder in its entirety which includes a box like casing 11, one open side of which is closed by a hinge door 12, which door may be locked in a closed position by inserting the key 13 into the lock 14 and turning the same to cause the bolt of the

lock to enter the usual keeper mounted on the jamb B or the adjacent side wall. The casing may be constructed of any desired material, such as wood, or metal and the bottom of the same is covered by a cushion or mat 15 which may be of rubber, felt or like material. The purpose of this cushion will be hereinafter fully explained. The top wall of the box like casing is provided with an annular opening 16 of a size to freely permit of the passage of the standard size milk bottle 17. Closing the under side of the opening 16 are swinging doors 18 and 19, which are hinged within the casing as at 20 and 21 respectively. The doors 18 and 19 are normally held in a closed position by springs 23 and 24 respectively, the tension of the swing 24 being greater than the tension of the spring 23 in order to return the door 19 to a closed position more quickly than the door 18. The door 19 is provided with outwardly extending tongues 25 which overlie the adjacent meeting edge of the door 18 to prevent inward swinging movement of the door 19 independently of the door 18.

Pivoted to the door 18 on the inside thereof adjacent its outer edge is a weighted member 26, the weight of the same serving to normally suspend the member in a vertical position due to the force of gravity. The bottom edge of the weighted member 26 is cut away to provide a seat 27 of a shape to snugly fit upon the top of the milk bottle 17 as clearly shown in Figure 4 of the drawings.

From the description thus far, it will be understood that upon insertion of a milk bottle through the opening 16 in a manner shown in Figure 2 of the drawing, the weight of the bottle will tend to swing the doors 18 and 19 inwardly, the weight member 26 always remaining in a vertical position, and for accommodating the weight in its downward movement, I provide a pocket 27' in the adjacent side wall of the casing so that the said weight may swing out of the path of downward movement of the bottle. When the bottle is released and dropped upon the cushion 15, the shock is arrested by the said cushion whereupon the springs 23 and 24 act to return the doors 18 and 19 respectively to

their closed position, it being appreciated that the door 19 is the first to fully return to closed position due to the excess tension of the spring 24 over the spring 23. When the doors are fully closed as shown in Figure 3, the seat 27 of the member 26 receives the top of the bottle 17, thus the doors are prevented from being pushed to open position. For the purpose of preventing accidental swinging of the weighted member 26 to a position which might release the doors, I provide flat arms 28 fixed to the undersides of the doors 18 and 19 and which arms extend inwardly and downwardly toward each other. The opposite sides of the weighted member 26 are provided with recesses or notches 29 for accommodating the free ends of the arms 28. These arms act as stops for limiting swinging movement of the member 26 when the door is in a closed position.

From the foregoing description it will be understood that the holder when empty is always accessible by the milkman for depositing a bottle of milk therein, but the presence of the bottle of milk within the casing serves to lock the entrance doors 18 and 19 against tampering by unauthorized persons. The bottle 17 may be readily removed by the authorized person having the necessary key 30 to unlock the door 12. Although no means has been shown for securing the holder to a support, it will be appreciated that any well known type of supporting bracket may be used for such purpose.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

Having thus described my invention, what I claim as new and desire to secure by Letters Patent, is:

1. A milk bottle holder comprising a box like casing having an opening in the top wall thereof, a pair of hinged doors, spring means for holding said doors in a closed position over said opening, and means carried by one of said doors for seating upon a milk bottle dropped into said casing for locking the same against movement to an open position.

2. A milk bottle holder comprising a box like casing having an opening in the top wall thereof, a pair of hinged doors, spring means for holding said doors in a closed position over said opening, and means carried by one of said doors for seating upon a milk bottle dropped into said casing for locking the same against movement to an open position, said means including a weighted member pivoted to said door.

3. A milk bottle holder comprising a box

like casing having an opening in the top wall thereof, a pair of hinged doors, spring means for holding said doors in a closed position over said opening, and means carried by one of said doors for seating upon a milk bottle dropped into said casing for locking the same against movement to an open position, said means including a weighted member pivoted to said door, and means for preventing swinging movement of said weighted member when in seated position upon a milk bottle.

4. A milk bottle holder comprising a box like casing having an opening in the top thereof, a key controlled door for access to the interior of said casing, a pair of hinged doors mounted on said casing for inward swinging movement, springs tending to normally hold the respective doors in their respective closed position beneath said opening, the springs acting upon one door being of a stronger tension than the spring acting upon the other door for closing one door faster than the other, a member pivoted to the weaker spring actuated door for overlying the top of a milk bottle when dropped into said casing through said opening and past said door.

5. A milk bottle holder comprising a box like casing having an opening in the top thereof, a key controlled door for access to the interior of said casing, a pair of hinged doors mounted on said casing for inward swinging movement, springs tending to normally hold the respective doors in their respective closed position beneath said opening, the spring acting upon one door being of a stronger tension than the spring acting upon the other door for closing one door faster than the other, a member pivoted to the weaker spring actuated door for overlying the top of a milk bottle when dropped into said casing through said opening and past said door, and means carried by said doors for limiting movement of said member in opposite direction.

6. A milk bottle holder comprising a box like casing having an opening in the top thereof, a key controlled door for access to the interior of said casing, a pair of hinged doors mounted on said casing for inward swinging movement, springs tending to normally hold the respective doors in their respective closed position beneath said opening, the spring acting upon one door being of a stronger tension than the spring acting upon the other door for closing one door faster than the other, a member pivoted to the weaker spring actuated door for overlying the top of a milk bottle when dropped into said casing through said opening and past said door, and a cushion on the bottom of said casing for arresting the shock of a bottle dropped therein.

7. A milk bottle holder comprising a box like casing having an opening in the top

thereof, a pair of hinged doors mounted on said casing for inward swinging movement, springs tending to normally hold said doors in a closed position under said opening, the 5 spring acting upon one door being of a stronger tension than the spring acting upon the other door for closing one door faster than the other, a weighted member pivoted to the weaker spring actuated door and provided with seats on the under side thereof 10 for seating upon the top of a milk bottle when dropped into said casing through said opening and past said door.

8. A milk bottle holder comprising a box 15 like casing having an opening in the top wall thereof, a pair of self closing doors closing said opening, pivoted members suspended from one of said doors for seating engagement with a milk bottle dropped into said 20 box like casing, and means for preventing swinging movement of said member when said doors are in closed position.

In testimony whereof I affix my signature.

JOSEPH PSAILA.
